UNITED STATES PATENT OFFICE.

CHARLES BLACKADAR, OF LYNN, MASSACHUSETTS, ASSIGNOR OF ONE-HALF TO GEORGE H. SIMONDS, OF SAME PLACE.

HEEL.

SPECIFICATION forming part of Letters Patent No. 634,743, dated October 10, 1899.

Application filed November 30, 1898. Serial No. 697,866. (No model.)

To all whom it may concern:

Be it known that I, CHARLES BLACKADAR, a subject of the Queen of Great Britain, residing at Lynn, in the county of Essex and State of Massachusetts, have invented certain new and useful Improvements in Heels; and I do hereby declare the following to be a full, clear, and exact description of the invention, such as will enable others skilled in the art to which it appertains to make and use the same.

My invention relates to an improvement in heels for boots or shoes, and particularly to rubber heels.

The object of my invention is to produce a heel which shall have all of the virtues of rubber heels and at the same time present an outer surface of leather, so that it may be in appearance the same as ordinary leather heels.

In addition it is my object to provide the heel with a tread portion of rubber which as it wears away may be pushed farther out by means of layers of material placed under it, and, further, in securing a tread portion to the heel in such manner that it may be turned over when one tread-surface is worn and a new tread-surface substituted for the worn one, besides which objects my invention contemplates the renewing of the rubber tread portion when worn out by a new tread portion which may be easily slipped into the heel in place of the old one.

To these ends, therefore, my invention consists in the improvement in heels hereinafter described, and particularly pointed out in the claims.

In the drawings illustrating the preferred form of my invention, in which like reference-numerals refer to like parts throughout, Figure 1 is a side elevation of my improved heel.

Fig. 2 is a medial longitudinal sectional elevation. Fig. 3 is a medial transverse sectional elevation, and Fig. 4 is a perspective view showing the heel turned bottom up.

1 indicates the leather shell of my heel, which is preferably made of a strip of leather which begins at the middle of the breast of the heel and extends around the sides of the same, returning to the middle of the breast of the heel from the other side, where it is united

to the beginning end by a seam of stitches or by any other suitable means.

2 indicates the top of the heel, which consists of a piece of leather fitting inside of the outer strip 1, being sewed thereto by a seam of 55 stitches 3 or secured thereto in any other suitable manner. The strip 1 and the top 2 together form a leather shell which presents to the eye when polished the same appearance as ordinary leather lift-heels. In this connection it should be observed that the leather will take and retain any desired color in the same manner as the leather of ordinary heels. This constitutes an important advantage over those heels in which the rubber extends to 65 the edges, which, as is well known, will not retain the color as will leather.

While I have described the shell of my heel as made of a strip of leather extending around the outside thereof, having attached thereto 70 a top made of a separate piece of leather and sewed to the strip, I do not wish to restrict myself to precisely such method of making the shell, as I consider that it is within the purview of my invention to make the shell of 75 a single piece of leather or vulcanized fiber or leather board stamped or pressed to the desired form.

4 indicates the rubber tread portion of my heel, which fits within the shell and is adapted to be held therein by the convex sides 5 of the shell, which engage the corresponding concave sides of the rubber tread portion 4. It will be observed that the sides of the rubber tread portion are concaved around the entire 85 outside of the same, while the breast of the heel is a plane surface. This is necessitated by the fact that the outside of my heel must present to the eye substantially the same appearance as that of ordinary heels. 90

In order to provide a support for the breast of the tread portion, I provide it with two projections 6, which project into two corresponding recesses in the inside of the strip of leather which forms the breast of the heel. 95 The tread portion is to be made symmetrical about a horizontal plane centrally located between the top and bottom of the tread portion. This permits the tread portion to be turned over when one face shall have become 100

irregularly worn in walking, so as to present a new face to the wear.

As the outer surface of the tread portion wears away and it becomes desirable to project it farther out to bring it to its proper elevation thin pieces of cork 7 or other suitable material may be placed under the tread portion, between it and the top of the shell. These pieces of cork may be made of such thickness as to efficiently support the tread portion when the worn surface is inserted into the shell—that is to say, in order to adequately support the tread portion a wedge-shaped piece of cork 7 may be inserted under 15 the tread portion to fill up the space worn away.

In use the shell is first attached to the heel-seat of the boot or shoe by means of a seam of stitches or by nailing, as may be desired, 20 and then the removable and reversible tread portion of rubber is pressed into the shell, in which it is held by the elasticity of the rubber, which will be slightly compressed in the process of insertion, so that it shall be firmly 25 held in the shell and capable of being raised as it wears away by washers of any suitable material interposed between the top of the shell and the upper side of the tread portion of rubber and which tread portion may also 30 be readily renewed when worn out. If desired, one surface of the tread portion of rubber may be made rough, as shown at 8, and the other surface may be made smooth, so that it may be turned over to adapt it for use 35 under different conditions—as, for instance, the rough portion may be used during icy or wet weather and the smooth portion may be used during fair weather.

I am aware that it has been proposed in the 40 patent to Blake and Libby, No. 105,389, to cover a solid block of wood or composition with a thick band of leather; but I am not aware that it has been proposed to provide a leather-heel shell with a removable reversible tread portion of rubber. I am also aware of the patent 45 to Randolph, No. 473,590, dated April 26, 1892; but my invention is clearly distinguished from what is shown in that patent by the fact that the outer surface of my heel is composed 50 of one integral piece of leather, with the grain thereof on the outside, whereas in the Ran-

dolph heel the socket to receive the rubber block is made by a series of lifts of leather provided with a recess extending into them, besides which, as above suggested, the rubber tread portion of my heel is reversible, being made symmetrical in form about a medial horizontal plane.

Having thus described my invention, I claim as new and desire to secure by Letters 55 Patent of the United States—

1. As an article of manufacture a heel for boots or shoes having an outer shell of leather and a tread portion of rubber, and a washer of suitable material interposed between the 60 top of the shell and the upper side of the tread portion, substantially as described.

2. A heel for boots or shoes, having a shell of hard material provided with a small cavity in the inside of the body of the breast thereof, and a removable, reversible tread portion of rubber provided on its breast with a projection complementary to the cavity on the inside of the breast of the shell and adapted to engage with and fit in said cavity to assist in 70 holding the tread portion in the shell, substantially as described.

3. A heel for boots or shoes, having an outer shell of hard material, the sides and rear of the shell being convex on their inner sides, 75 a removable, reversible, and imperforate tread portion of rubber having its sides and rear concave and complementary in shape to the inside of the sides and rear of the shell and having its upper and lower faces of the 80 same size, whereby the tread portion is adapted to be held either side up by the shell and with its upper face at varying heights therein so that the tread-face is always projected from the shell the same distance although worn 85 thinner by use, and a washer, said tread portion being adapted to be maintained in position by means of said washer interposed between the upper face of the tread portion and the lower side of the top of the shell, substantially as described.

In testimony whereof I affix my signature in presence of two witnesses.

CHARLES BLACKADAR.
